UNITED STATES PATENT OFFICE.

CHARLES EDWARD CARTER, OF CINCINNATI, OHIO, ASSIGNOR OF TWO-
THIRDS TO LUENA CARTER AND LOUIS WIRTH, OF CINCINNATI, OHIO.

CUSPIDOR.

SPECIFICATION forming part of Letters Patent No. 743,446, dated November 10, 1903.

Application filed February 25, 1903. Serial No. 145,068. (No model.)

To all whom it may concern:

Be it known that I, CHARLES EDWARD CARTER, a citizen of the United States, residing at Cincinnati, in the county of Hamilton and State of Ohio, have invented a new and useful Cuspidor, of which the following is a specification.

This invention relates generally to cuspidors, and more particularly to one specially adapted for use in railway-cars, the object being to provide a cuspidor which can be quickly and easily flushed and emptied, thereby maintaining the same in a thoroughly-sanitary condition.

15 The invention consists, essentially, of an upper section secured upon the floor of a car above an opening in said floor and a lower portion or bowl pivoted to the under side of the floor and adapted to rest directly beneath 20 said opening in the floor, a spring for normally holding the bowl or lower portion in a horizontal position, and a spring-actuated push-rod adapted to engage the lower portion or bowl for the purpose of throwing the same 25 down when it is desired to empty the same.

The invention consists also in certain details of construction hereinafter fully described and pointed out in the claims.

In the drawings forming a part of this specification, Figure 1 is a perspective view of a cuspidor constructed in accordance with my invention. Fig. 2 is a vertical longitudinal-sectional view of the same. Fig. 3 is a transverse section on the line 3-3 of Fig. 2, and Fig. 4 is a detail perspective view of the bowl or lower section.

30 In carrying out my invention I construct a cuspidor in two sections—namely, the upper section A, which is arranged upon the floor of the car, the lower section B, arranged upon the under side of said floor, said floor being designated by the letter C, and it will be noted that the floor has an opening C', over which the upper section is placed and 35 under which the lower section is arranged. The upper section consists of the cylindrical side portion A', having ears A², by means of which said upper portion is connected to the floor, and the usual funnel-shaped top or 40 cover A³, having the central opening A⁴, from

which depends the pipe A⁵, passing through the floor.

The lower section B is essentially bowl-shaped and is pivoted at B' to the under side of the floor by means of a hinge and is provided at one side with a laterally-projecting grooved lip B². A spring-bar D is connected at D' to the under side of the floor and bears at its free end upon the under side of the bowl, as shown at D², for the purpose of normally holding the bowl in a horizontal position, so that it serves as the receptacle portion of the cuspidor.

A push-rod E passes through an opening in the floor and engages the lip projecting from the side of the bowl, said push-rod working through an opening E' in the cover A³, the lower end E² of the rod contacting with the lip B², and inasmuch as the lip is somewhat elongated and grooved throughout its entire length and arranged at one side of the hinge it is obvious that the push-rod will remain in contact with the lip during the entire downward movement of the bowl, which is caused by pressing down upon the push-rod E. 65 A spiral spring E³ surrounds the push-rod between the floor and a collar E⁴, made fast upon the push-rod, and against which the upper end of the spring E³ presses, so that the moment pressure is removed from the push-rod 70 the spring will return said rod to its normal position and the spring D will raise the bowl to a horizontal or closed position. The upper end of the push-rod is provided with a head E⁵. Whenever it is desired to cleanse 75 and empty the cuspidor, it is flushed or flooded with the water, and by pushing down upon the push-rod the entire contents will be instantly discharged, leaving the cuspidor thoroughly cleaned and sanitary.

Having thus fully described my invention, what I claim as new, and desire to secure by Letters Patent, is—

1. A cuspidor comprising an upper section 95 secured to the floor and covering an opening in said floor, a bowl-shaped lower section hinged to the under side of the floor, and having a grooved lip arranged at one side thereof, a spring for normally holding the bowl in a horizontal position, and a spring-actuated 100

push-rod connected to the upper section, the lower end of said push-rod being adapted to engage the grooved lip of the bowl, as specified.

2. A cuspidor, comprising an upper portion adapted to be secured to the floor and cover an opening in said floor, the push-rod passing through the upper section, the coil-spring surrounding the push-rod, the collar connected to said push-rod, and the bowl-shaped lower portion, hinged to the under side of the floor, a spring secured to the floor,

the free end thereof bearing upon the under side of the bowl, and the laterally-projecting lip arranged on one side of the hinge, said lip being grooved throughout its entire length 15 whereby the lower end of the push-rod can contact with said lip during the entire movement of the bowl, substantially as set forth.

CHARLES EDWARD CARTER.
